UNITED STATES PATENT OFFICE.

JOE J. KOUKOL, OF CUBA, KANSAS.

EMERY-WHEEL STAND.

Application filed April 6, 1921. Serial No. 459,044.

To all whom it may concern:

Be it known that I, JOE J. KOUKOL, a citizen of the United States, residing at Cuba, in the county of Republic and State 5 of Kansas, have invented certain new and useful Improvements in Emery-Wheel Stands, of which the following is a specification, reference being had to the accompanying drawings.

10 This invention relates to a grind stone or emery wheel stand and has for its object to provide a device of this character wherein one or more grind stones or emery wheels can be attached and operated simultaneously to abrade different articles at the same time.

Another object is to provide a device of this character including means for holding tools in position before the emery wheel.

20 A still further object of the invention is to provide means whereby a harrow disk may be positioned and efficiently sharpened, said means permitting rotation of the disk over the periphery of the rotating emery 25 wheel at the desired inclination.

With these and other objects in view, the invention consists in the improved construction and arrangement of parts to be herein-after more particularly described and more 30 fully claimed and illustrated in the accompanying drawings, in which:

Figure 1 is an end elevation of the emery wheel stand,

Figure 2 is a side elevation,

35 Figure 3 is a top plan view,

Figure 4 is a section taken on the line 4-4 of Figure 1,

Figure 5 is a front elevation of the gear housing,

40 Figure 6 is a side elevation showing the tool rest applied,

Figure 7 is a detailed sectional view of the tool rest,

45 Figure 8 is an end elevation of the saw attachment,

Figure 9 is a side elevation of the structure shown in Figure 8, and

Figure 10 is a perspective view of one of the brackets of the saw table.

50 Referring to the drawings, 5 designates a stand including standards 6 and 7, the upper ends of each pair of standards 6 and 7 being connected to the adjacent standards by means of a bearing block 8. The feet 55 or lower ends of the standards are secured to skids 8^a which permit the stand to be used

on soft ground. A shaft 9 is rotatably mounted upon the bearing block 8, a bearing plate 10 being disposed over the shaft and upon the bearing blocks 8 to maintain 60 the shaft in position. The ends of the shaft 9 extend beyond the standards and are intended to receive grind stones or emery 65 wheels 11, the wheels being disposed in spaced relation to the standards to prevent contact of the article being abraded with the stand. A conventional form of pulley 12 is secured to the intermediate portion 70 of the shaft 9 and is adapted to be connected to a source of power.

In order to permit the efficient abrading of tools, there is provided a novel form of tool rest consisting of a bar 13 which is secured to one end of the stand, that is, one end of the bar is secured to one of the standards 7 and the opposite end portion to one of the standards 6. One end of the bar is bent back upon the main position of the bar to provide an arm 14 which serves to space the tools to be sharpened from the 80 standards. The arm 14 is provided with a slot 15 adapted to receive the U-shaped clamp 16, bolts 17 being carried by the end of the clamp to permit adjustment and tightening of the same. A tool support 17 85 is used, said support being substantially L-shaped. The end portion 18 of the support is adapted to be secured by a suitable clamp 9' to the stand, while the end portion 19 of the support is extended through the 90 clamp 16 and is secured to the arm 14 substantially in a vertical position, the extremity of the end portion 18 being provided with a socket 20 for the reception of a tool rest 21. An important feature of this support is that it can be maintained at various 95 positions in view of the fact that the slot 15 is made relatively long so that the clamp 16 may be adjusted longitudinally of the arm 14. In addition to this, the end portion 19 of the standard may be moved to various inclined positions, so that any form of tool may be efficiently abraded with the use of this support.

In order to sharpen harrow disks, cultivator shovels and like implements, there is provided a novel form of support comprising a bar 22 adapted to extend across the stand and secured thereto by means of clamps 23 which permit oscillating movement of the bar. The end portion 24 of the bar is extended at right angles to said

bar and provided with an opening 25 for the reception of the set screw 26. The set screw 26 is adapted to be disposed in one of a series of openings 27 formed in a segmental member 28. The end 29 of the segmental member is secured to one of the stands, while the end 30 is secured to the bar 13. By this means, the bar 22 may be adjusted and secured in various positions according to the inclinations desired for sharpening a particular implement. The opposite end 31 of the bar is extended in the opposite direction to that of the end 24, and then back upon the bar to provide an arm 32 which is positioned substantially in spaced parallel relation to the bar. A pair of U-shaped clamps 33 are secured to the arm 32, and have their ends connected by means of bolts 34, the purpose of which will be hereinafter described.

A separable housing 35 is adapted to be disposed between the clamps 33, the meeting edges of the housing being maintained substantially at right angles to provide ears 25 adapted to be disposed between the ends of the clamps 33 and to be secured by means of the bolts 34. By this means, the clamps not only serve to connect the housing to the arm 32, but also provide means for holding the 30 separable positions of the housings in engagement with each other. A gear 36 is mounted within the housing and is adapted to engage a worm gear 37 mounted in a supplemental housing 38 carried by one of the 35 separable portions of the housing 35, the worm gear 37 including a shaft 39, and having a handle 40 on one end thereof through the medium of which the gear 36 is rotated. A handle 41 is secured to the housing 38 and 40 is disposed at right angles to the shaft 39 and housing 35. The shaft 36^a on which the gear 36 is mounted projects beyond the housing 35 and is threaded. A disk A is intended to be disposed upon the shaft 36^a 45 and secured by means of a nut 42 including a handle. In use, after the disk has been attached to the shaft 36^a, the housing is moved toward the emery wheel through the medium of the handle 41 and the clamps 33. 50 In view of the distance between the arm 32 and the stand, the disk will be maintained in an inclined position. This position may be regulated by adjusting the end 24 of the segmental member 27. The operator holds the disk in engagement with the emery wheel through the medium of the handle 41, and at the same time rotates the gears and the disk A through the medium of the handle 40, the emery wheel being rotated by independent means. By this arrangement, all 55 portions of the disk receive the same amount of abrading. When the disk has been sharpened, the housing may be moved away from the emery wheel through the medium 60 of the handle 41 and the disk A removed.

The device can be arranged to serve as a wood saw machine by removing one of the emery wheels from the end of the shaft 9, and substituting a saw blade 42^a. To properly support timber before the blade there is 70 provided a novel table structure embodying a U-shaped bracket 43, the ends of the arms of the bracket having arcuate recesses 44 adapted to engage the bar 22 of the bar 13. The arms of the brackets are also provided 75 with recesses 45 adapted to engage the arm 32 of the bar 22 or the arm 14 of the bar 13. This bracket is intended to support one end of a table 46. The opposite end of the table is supported by means of a bracket 47 which 80 is secured to one of the standards. The table 46 is provided with a slot through which the saw projects. A timber guide 48 is mounted on the table adjacent the saw blade.

From the foregoing it will be readily 85 seen that this invention provides a novel form of grind stone and emery wheel stand whereby any device regardless of its shape or size, may be readily positioned for abrading or sharpening, and wherein two persons may use the device at the same time. By the novel inclinations of the standards 90 6 and 7, and the skids 8^a, the operator may apply the desired weight against the article to be treated without danger of tilting the 95 stand.

What is claimed is:

1. A device of the character described, comprising a stand, a rod journaled on the stand, one end of said rod being adapted to 100 engage a member having a series of openings, the opposite end of the bar being extended back upon the bar, gear means movably connected to the last mentioned end of the bar, means for securing an implement to 105 the gear means, and means for rotating the gear means and for moving the same toward the abrading means.

2. In combination with a stand, abrading means mounted on the stand, a supporting bar mounted on one end portion of the stand in spaced relation to the abrading means, a shaft rotatably mounted on one side of the stand, means for operatively connecting said shaft to the connecting bar, one 110 end of said shaft being provided with tool supporting means, a second shaft mounted on the opposite side of the stand, means for adjustably connecting one end portion of the second mentioned shaft to the connecting bar, and tool supporting means adjustably mounted on the second mentioned shaft.

3. In combination with a stand including end members, rods connecting said end members, a shaft rotatably mounted on the end members, abrading means on each end of the shaft, a supporting bar mounted on and extending longitudinally of the stand, one end portion of the bar being reverted to provide a supporting arm, the opposite end 125 130

of said bar being extended in angular relation to the major portion of the bar, and provided with a set screw, said angularly extended end being disposed parallel to the 5 adjacent end portion of the stand, a second supporting bar mounted on said end member and extending transversely of the stand, one end portion of said bar being reverted to provide a supporting arm, an arcuate strip 10 secured at one end to the stand and at its opposite end to the central portion of the second mentioned supporting arm, an arcu-

ate strip secured at one end to the stand and at its opposite end to the central portion of the second mentioned supporting bar, said 15 arcuate strip having a series of openings adapted to receive the set screw of the first mentioned supporting bar, and implement supporting means adjustably connected to each of said supporting arms. 20

In testimony whereof I hereunto affix my signature.

JOE J. KOUKOL.
